(57) **CLAIM**

The ornamental design for an electronic device, as shown and described.

DESCRIPTION

FIG. 1 is a perspective view of the electronic device;

FIG. 2 is a front view of the device;

FIG. 3 is a side view of the device;

FIG. 4 is a rear view of the device;

FIG. 5 is a top view of the device;

FIG. 6 is a side view of the device; and,

FIG. 7 is a bottom view of the device.

1 Claim, 7 Drawing Sheets
